UNITED STATES PATENT OFFICE.

KRAFT BOOTH, OF PHILADELPHIA, PENNSYLVANIA, ASSIGNOR TO GILLINDER & SONS, INC., OF PHILADELPHIA, PENNSYLVANIA, A CORPORATION OF PENNSYLVANIA.

DESIGN FOR AN ARTIFICIAL-LIGHT SHADE.

41,893.

Specification for Design.

Patented Nov. 7, 1911.

Application filed September 2, 1911. Serial No. 647,456. Term of patent 14 years.

To all whom it may concern:

Be it known that I, KRAFT Booth, a citizen of the United States, and resident of the city and county of Philadelphia and State of Pennsylvania, have invented a new, original, and ornamental Design for an Artificial-Light Shade, of which the following is a specification, reference being had to the accompanying drawing.

The said drawing is a perspective view

of an artificial light shade showing my new design.

I claim—

The ornamental design for an artificial light shade, as shown.

KRAFT BOOTH.
